UNITED STATES PATENT OFFICE.

WILLIAM G. HURST, OF NEW BRIGHTON, ENGLAND.

CLIP FOR ATTACHING INFLATERS TO CYCLES.

SPECIFICATION forming part of Letters Patent No. 669,697, dated March 12, 1901.

Application filed January 6, 1899. Serial No. 701,370. (No model.)

To all whom it may concern:

Be it known that I, WILLIAM GEORGE HURST, a subject of the Queen of Great Britain and Ireland, and a resident of 21 The 5 Quadrant, New Brighton, near Liverpool, England, have invented a certain new and useful Clip for Attaching Inflaters to Cycles, (for which I have obtained a patent in Great Britain, No. 26,045, bearing date December 9, 10 1898,) of which the following is a specification.

This invention relates to clips such as are 15 used for attaching inflaters to the frames of cycles; and it consists of a simple form of clip by the use of which the inflater can be easily and conveniently attached for carriage or detached for use. Moreover, it is light and neat in appearance and can be manufactured at a 20 low first cost.

In order that my invention may be fully 25 understood and ascertained, I append drawings, in which—

Figure 1 is an edge view of clip, showing it 30 in position holding the inflater to the frame-tube. Fig. 2 is a front view of same. Fig. 3 is an edge view of the clip free from the frame 35 and inflater. Fig. 4 is an edge view of steel strip. Fig. 5 is a front view of same. Fig. 6 is a front view of elastic strips, H-piece, loops, and tabs. Fig. 7 is an enlarged view of loops, 40 showing action of the tabs.

Z indicates the inflater, and X that tube of 45 the frame to which it is attached.

A steel, celluloid, or other strap A of any 50 convenient width is bent so as to form two approximately semicircular parts a and a' , the concave sides of which are presented in 55 opposite directions. This is shown clearly in Fig. 4. The two semicircular parts are joined by a short straight portion a^2 of sufficient 60 length to keep the inflater at a slight distance 65 from the frame-tube. Each end of the strip is bent so as to form a hook a^3 , the concave 70 surface of which is presented in an opposite direction to that of the concavity of the semicircle of which it forms part.

To the middle part of the straight portion 75 a^2 of the strip A is attached a metal clip a^4 , having approximately the shape of the letter H. This is preferably inserted through a slot 80 a^5 and then turned through a quarter of a circle, so as to occupy the position shown in Fig. 3, one of the parallel members then ex-

tending across each side of the clip A and the transverse connecting member passing through the slot a^5 . To each of the parallel 55 members of this clip is attached one end b of one of two india-rubber or other elastic strips or bands B and B', each of which has one of two rectangular loops C and C' attached to its other or free end b' . The length of each 60 band, together with its attached loop, is such that when the band is slightly extended longitudinally and folded around the frame-tube or inflater the hook a^3 on the end of the strip A can be hooked into the loop, the whole then 65 assuming the position shown in Figs. 1 and 2, the inflater and frame-tube occupying the concave portions of the steel strips and being held therein by the tension of the elastic bands.

To the free end of each of the rectangular loops is hinged a tab D in such manner that it can turn freely upon one of the ends of the loop. This tab is of such shape that it can 70 be conveniently grasped by the fingers when hooking it on the hook a^3 , thus facilitating the closing. In addition, when it is required to release the inflater all that is necessary is to turn the tab on its hinge through about a 75 half-circle to the position shown in dotted 80 lines in Fig. 7, when the pressure of the tab brings the loop end to the position shown in dotted lines, thus allowing it to escape from the hook a^3 and release the inflater from the 85 clip or the clip from the frame-tube.

Having now described my invention, what I claim as new, and desire to secure by Letters Patent, is—

1. In a clip for attaching an inflater to the frame-tube of a cycle, the combination of a 90 rigid strip A having concave parts a and a' and hooked ends a^3 , elastic strips B and B' one end of each of which is attached to the strip A, and loops C attached one to each of the strips B and B' in such manner as to be 95 capable of being hooked to the ends a^3 , substantially as shown and described.

2. In a clip for attaching an inflater to the frame-tube of a cycle, the combination of a rigid strip A having a slot a^5 , concave parts 100 a and a' , a straight part a^2 , two hooks a^3 , a clip a^4 , two elastic strips B and B', and two loops C and C', attached one to each of the strips B and B' in such manner as to be ca-

pable of being hooked to the ends α^3 , substantially as described and shown.

3. In a clip for attaching an inflater to the frame-tube of a cycle, the combination of a rigid strip A having a slot α^5 , concave parts α and α' , a straight part α^2 , two hooks α^3 , a clip α^4 , two elastic strips B and B', two loops C and C', attached one to each of the strips B and B' in such manner as to be capable of being hooked to the ends α^3 , and two tabs D

by means of which the loops C and C' may be easily and conveniently liberated from the ends α^3 , substantially as shown and described.

In witness whereof I have hereunto set my hand in presence of two witnesses.

W. G. HURST.
